Patented Mar. 11, 1919.

FIG. 1.

FIG. 2.

FIG. 3.

ERIC E. ESSEN, *INVENTOR.*

BY Frank Carlson
ATTORNEY

UNITED STATES PATENT OFFICE.

ERIC E. ESSEN, OF BROOKLYN, NEW YORK.

VALVE-LIFTER.

1,296,784.

Specification of Letters Patent. Patented Mar. 11, 1919.

Application filed March 16, 1918. Serial No. 222,941.

To all whom it may concern:

Be it known that I, ERIC E. ESSEN, a citizen of the United States, and a resident of 1043 Rogers avenue, in the county of 5 Kings, borough of Brooklyn, city and State of New York, have invented certain new and useful Improvements in Valve-Lifters, of which the following is a specification.

This invention relates to valve lifters, and 10 especially to that class wherein a C bracket is provided with an adjustable lever.

One advantage of this invention is to provide a valve lifter so formed as to reach the parts of a valve to be removed without necessitating the previous removal of other parts. 15

Another advantage is to provide a valve lifter which has a lever which is easy to operate and accessible in all positions.

A further advantage is to have a valve 20 lifter provided with a self locking lever.

A still further advantage is to have in a valve lifter a lever which is fulcrumed upon a bracket and provided intermediate of its ends with a series of holes to receive a pin 25 for different positions for said fulcrum.

Yet another advantage is to have a valve lifter having a lever provided with a self adjusting foot.

Further advantages and possibilities will 30 become apparent as the specification proceeds.

Referring to the drawing, Figure 1 is a side view of an apparatus embodying the present invention in operative relation to a 35 valve shown in vertical section.

Fig. 2, is a similar view with the apparatus of the present invention in its final useful position.

Fig. 3, is a perspective view of the bracket 40 6 of Figs. 1 and 2.

Like numerals denote the same parts throughout the views.

In repairing or adjusting internal combustion engines it is frequently found that 45 inlet and exhaust valves must be removed for regrinding or replacement. The removal of such valves has always presented great difficulties and been a source of considerable trouble and waste of time. The

50 valve springs are exceedingly powerful, frequently exerting a pressure of 100 lbs., and this must be entirely overcome in order to remove the washer beneath the spring and the key supporting the same. This would 55 be fairly easy of accomplishment if it were

not that the mentioned parts are so inaccessible because of the superstructure of the engines, especially the last V type motors.

It is proposed to remedy this condition of affairs by using a valve lifter which is 60 very simple in construction and operation. It consists of a bracket 6 exteriorly ribbed and provided at its upper extremity with a fulcrum block 9, a lever 7 pinned therein, and at the lower extremity a fork 3. 65

When a valve 5 is to be removed, the cap fitting thread 8 is first removed, exposing the valve head. The bracket 6 is passed down into the channel between the cylinder blocks and set under washer 1 so that fork 70 3 straddles valve shank 5. Then the adjustable foot 10 is superposed upon the head of valve 5 to prevent the latter from rising. If the position of lever 7 is too horizontal too little leverage will result, so the pin 75 3 may be withdrawn from fulcrum block 9 and pushed through another hole in the lever so that a starting position would appear similar to Fig. 1. The spring 2 bears up against cylinder blocks 11 and down upon 80 washer 1, which latter rests upon key 4, thus retaining the valve 5 in closed position. If the lever 7 is now pushed over to the position shown in Fig. 2 the pin in block 9 will pass dead center above the foot 10 and the valve, 85 and will thus remain, self locked. Bracket 6 having been raised, it will be seen that fork 3 has forced up the washer 1 and compressed the spring 2, exposing the key 4, which is then fully accessible. In view of 90 the fact that the lifter is in locked position, both hands are free and attention may be directed to removing the key. This being comparatively easy, being accomplished, the lever 7 is drawn to the left, and the bracket 95 lifted out from under the washer. The washer and spring, now finding no lower limit immediately project downward and release valve shank 5, which may now be picked out with ease. 100

As it is possible to slightly modify the lever 7 and also to make an open slot tending downward of the hole in the fulcrum block 9, I reserve all rights to make all such modifications, as may be deemed compatible with the scope of the appended claims. 105

Having thus fully described my invention, I desire to obtain by Letters Patent:—

1. In combination in a valve lifter, a bracket having a lower bifurcated portion 110

2
and a slotted block upon its upper portion, a lever movably pinned in said slotted block, and a foot movably jointed to said lever to provide a secondary fulcrum for the same, 5 there being a series of holes in said lever to provide different leverages thereof.

2. The combination in a valve lifter, of a bracket provided with a lower bifurcated portion and in its upper extremity a pin, 10 with a lever operatively supported by said pin passing through one of a series of holes

in said lever, and a foot movably joined to 15 said lever.

Signed at 226 Flatbush Ave., in the borough of Brooklyn, county of Kings, city and State of New York this 14 day of March, 1918.

ERIC E. ESSEN.
